UNITED STATES PATENT OFFICE.

RENÉ E. DUPLESSIS, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

TRIMMING MACHINE.

Application filed July 6, 1920. Serial No. 394,184.

To all whom it may concern:

Be it known that I, RENÉ E. DUPLESSIS, a citizen of the United States, residing at Beverly, in the county of Essex and State 5 of Massachusetts, have invented certain new and useful Improvements in Trimming Machines; and I do hereby declare the following to be a full, clear, and exact description of the invention, such as will enable 10 others skilled in the art to which it appertains to make and use the same.

The present invention relates to trimming machines and more particularly to upper trimming machines which are employed in 15 the manufacture of stitch-down shoes.

In making stitch-down shoes of one type, an upper of canvas is shaped on a last and formed with an outturned flange to which a relatively stiff and thin insole of rubberized canvas is secured by means of a 20 row of staples inserted adjacent to the line where the outturned flange joins the body portion of the upper. A rubber welt is subsequently laid upon the outturned flange 25 of the upper and is sewed to the flange and the insole, which welt is thereafter vulcanized or otherwise directly secured to an outsole outside the trimmed edges of the upper and insole. In order that this method 30 may be followed, the marginal portions of the upper and insole must be trimmed uniformly distant from the body of the shoe before the welt and outsole are applied to the shoe.

35 One of the objects of the present invention is to provide a machine for thus trimming the edges of the outturned flange and the insole.

With this and other objects in view, the 40 features of the present invention consist in certain constructions, arrangements and combinations of parts hereinafter described and claimed, the advantages of which will be obvious to those skilled in the art.

45 The several features of the present invention will be clearly understood from the following description and accompanying drawings, in which:

Figure 1 is a side elevation of a machine 50 embodying the features in their preferred form; Fig. 2 is a detail sectional view taken on the line 2—2 of Fig. 3; Fig. 3 is a front

elevation of the machine; Fig. 4 is a detail front elevation of a portion of the operating instrumentalities of the machine shown 55 as operating upon a partly constructed stitch down shoe; Fig. 5 is a sectional view taken on the line 5—5 of Fig. 4; and Fig. 6 is a transverse sectional view of a lasted upper and insole after being operated upon by 60 the machine, the welt and outsole of the shoe being shown by dotted lines.

The shoe illustrated in Fig. 6 comprises an upper 2 of canvas which is shaped on a last 4 so that its margin will form an outturned flange 6. The outturned flange 6 is fastened to an insole 8 of rubberized canvas by means of a row of staples or other fastening means 10 inserted adjacent to the crease or the line of junction with the body portion of the upper. The outturned flange and the insole require trimming so that their edges will be even and preferably uniformly distant from the aforesaid crease. The embodiment of the present invention illustrated 70 in the drawings, which is adapted to perform this trimming operation, comprises a stationary trimming shear 12 having a horizontal cutting edge 14, and a horizontally movable shearing knife 16, the cutting edge 75 of which works across the cutting edge of the stationary shear 12. In order to insure that the trimming cut shall be made a uniform distance from the junction line of the outturned flange and lasted portion of 80 the upper, the lower end of the stationary knife 12 is extended and shaped to slide in the crease or angle at said line so as to serve as a gage. The stationary shear 12 is secured at its upper end by a bolt 18 to an 85 overhanging portion 20 of the frame of the machine. The knife 16 is mounted on the forward end of a carrier bar 22 mounted so as to slide in the machine frame. The bar 22 is reciprocated by an eccentric 90 carried by the driving shaft 28 of the machine, the operating connection being formed by an eccentric strap 24. The shaft 28 is journaled in the frame and has a pulley 30 secured to one end thereof.

The illustrated machine is provided with a guide 32 having a kerf extending upwardly from its lower end to receive the marginal portions to be trimmed. The con-

fronting portions 34 and 35 formed by the kerf are separated only so far as to avoid binding the marginal portions, and they deflect and flatten uneven portions of the upper 5 and keep the latter in close relation to the insole. The confronting faces of the portions 34 and 35 preferably converge as shown by Fig. 5 to facilitate the passage of the work through the kerf. The guide 32 10 is arranged to slide up and down so that it may follow the contour of the body of the shoe without hindering the manipulation thereof, and for this purpose is provided with screw studs 36. These extend through 15 a slot in the portion 20 of the frame. A spring 38 acts on the guide 32 to keep its lower end in contact with the body of the shoe.

After the shoe has been trimmed as afore- 20 said a welt 40 and outsole 42 are stitched to the marginal extension. This is followed by vulcanizing or otherwise directly uniting the welt with the outsole outside the trimmed edges of the upper and insole.

25 While the features described above are well adapted for use in the type of machine illustrated in the drawings, it is to be understood that, except as defined in the claims, certain features of the invention 30 are not limited to use in a machine embodying any or all of the other features.

The nature and scope of the present invention having been indicated, and a machine embodying the several features of the 35 invention in their preferred form having been specifically described, what is claimed is:—

1. A shoe-trimming machine comprising 40 means arranged to trim the marginal portions of a plurality of superposed layers of material, and two confronting elements arranged to guide the untrimmed portions to said trimming means, one of said confronting elements being arranged to run on the 45 body of the shoe and to yield along lines substantially parallel to the planes of said layers.

2. A shoe-trimming machine comprising 50 means arranged to trim the marginal portions of a plurality of superposed layers of material, and a yieldable unit having confronting work-engaging portions arranged to guide the untrimmed portions of said marginal portions to said trimming means, 55 said unit being arranged to yield along lines substantially parallel to the planes of its confronting work-engaging faces.

3. A machine for operating upon the upper and sole of a stitch down shoe while the 60 parts are on a last having, in combination, means for trimming the edges of the outturned flange of the upper and sole, and means comprising converging elements for bringing the outturned flange and sole together in advance of said trimming means.

4. A shoe-trimming machine comprising 70 means arranged to trim the marginal extension formed by the upper and sole of a stitchdown shoe, and two cooperative elements arranged in confronting relation to 75 guide the untrimmed work to said trimming means, one of said elements being arranged to engage the body of the shoe and the upper face of said marginal extension and to yield in a direction away from the body of the shoe and along lines substantially parallel to the plane of the sole.

5. A machine for operating upon the upper and sole of a stitch down shoe having, 80 in combination, means for trimming the edges of the sole and the outturned flange of the upper, and means relatively to which the work is freely movable edgewise of the sole for guiding the untrimmed portion of said flange and sole to said trimming means, said 85 guiding means having confronting portions arranged to close separated portions of the flange and sole.

6. A shoe-trimming machine comprising 90 means arranged to trim the marginal extension of the upper and sole, and a yieldable work-guiding device having a channel arranged to guide the untrimmed portion of said marginal extension to said trimming means, said yieldable device being arranged 95 to bear on the body of the shoe so as to follow the contour thereof and take various positions automatically as the work is fed to trim progressively.

7. A machine for operating upon the upper and sole of a stitch down shoe while the parts are on a last having, in combination, 100 means for trimming the edges of the sole and the outturned flange of the upper, and means arranged to close separated portions 105 of said flange and sole in advance of the trimming locality, said closing means being yieldable and arranged to bear on the body of the shoe so as to follow the contour thereof as the shoe is fed to trim progressively.

8. A trimming machine having, in combination, a stationary trimming knife, a co-operating reciprocating trimming knife and a member yieldable transversely of the trimming cut for engaging opposite sides of the work to present the edges of the work to the action of the trimming knives. 115

9. A shoe-trimming machine comprising 120 means arranged to trim the marginal extension of the upper and sole, fixed means arranged to bear on the body of the shoe and thereby guide the latter relatively to said trimming means, and a device arranged to bear continuously on the upper face of the untrimmed portion of said marginal extension so as to guide the latter to said trimming means, said device being arranged to yield and formed to bear also on the body of the shoe so as to follow the contour thereof 125 130

and take various positions automatically as the work is fed to trim progressively.

10. A shoe-trimming machine comprising means arranged to trim the marginal extension formed by the sole and outturned flange of the upper of a stitch down shoe, and cooperative work-guiding elements

spaced a fixed distance apart and arranged to engage opposite faces of said extension in advance of the trimming locality so as to 10 close the outturned flange and the sole toward each other without clamping them.

RENÉ E. DUPLESSIS.
